(57) **CLAIM**

The ornamental design of the gemstone, as shown and described.

DESCRIPTION

FIG. 1 is a top view of an exemplary embodiment of a gemstone showing my new design;

FIG. 2 is a perspective bottom view of the gemstone of FIG. 1;

FIG. 3 is a right side view of the gemstone of FIG. 1; FIG. 4 is a rear view of the gemstone of FIG. 1; and,

FIG. 5 is a bottom view of the gemstone of FIG. 1. The portions of the gemstone that are not shown in the drawing do not form any part of the claimed design.
